UNITED STATES PATENT OFFICE.

JONAH REYNARD, OF TIFFIN, OHIO, ASSIGNOR TO THE LOOMIS MACHINE CO., OF TIFFIN, OHIO.

CABLE ATTACHMENT FOR DRILLING MACHINES.

Application filed February 12, 1923. Serial No. 618,549.

To all whom it may concern:

Be it known that I, JONAH REYNARD, a citizen of the United States, residing at Tiffin, in the county of Seneca and State of Ohio, have invented a new and useful Cable Attachment for Drilling Machines, of which the following is a specification.

This invention relates to an attachment for the main cable of a drilling machine, one of the objects of the invention being to provide a novel form of clamp for gripping the cable and holding it against movement relative to the drum or reel about which the cable is wrapped.

In many forms of drilling apparatus the main cable which carries the drill is extended over a mast and thence to a guide sheave and to the main reel. A spudding beam is mounted for oscillation and carries a wheel engaging a portion of the cable. The drill is lowered to the bottom of the hole and the main reel to which the cable is attached is then held against further movement. The spudding beam is swung downwardly and upwardly and, during each downward movement will produce a bend in a portion of the main cable and cause the drill to be lifted from its normal position. At this time the weight of the drill is transferred from the bottom of the hole to the held main reel and under ordinary conditions results in the tightening of the coils of the cable upon the reel. When the spudding beam moves upwardly the engaged portion of the cable will straighten out and the drill will drop to its normal position, thus relieving the main reel of the weight of the drill and allowing the tensioned portion of the cable on the reel to relax. During the operation of the machine the raising and dropping of the drill occurs from forty to fifty times or more per minute and as each of these operations results in the movement of the coils of the main cable relative to each other and to the reel the cable quickly generates heat as a result of friction. Consequently the cable will burn out or become otherwise badly damaged and considerable loss to the operator results.

It is an object of the present invention to provide the cable with a means whereby the rubbing together of the convolutions on the reel during the actuation of the drill is eliminated.

Another object is to provide an attach-

ment of this character which can be installed readily on a drilling machine and which will not interfere with the necessary paying out of the cable as the hole increases in depth.

With the foregoing and other objects in view which will appear as the description proceeds, the invention consists of certain novel details of construction and combinations of parts which will be hereinafter more fully described and pointed out in the claims.

In the accompanying drawings the preferred form of the invention has been shown. In said drawings.

Figure 1 is a side elevation of the attachment applied to a drilling machine and the main cable thereof, said machine and the elevated drill being indicated by broken lines.

Figure 2 is an enlarged section on line 2-2 Figure 1.

Figure 3 is an enlarged section on line 3-3 Figure 2.

Referring to the figures by characters of reference A designates the main frame of a drilling machine having a mast B and a spudding beam C. A sheave D is provided at the fulcrum end of the spudding beam and another sheave E is provided at the free end of the spudding beam. A cable F is connected at one end to the drill G and, at its other end to the main drum or reel H of the machine. This cable, a portion of which has been shown by full lines in Figure 1 is extended under the sheave E and over the sheave D and is coiled about the drum or reel H so that by rotating the same the cable can be paid out or taken up to lower or raise the drill preparatory or subsequent to each drilling operation.

The attachment constituting the present invention includes a clamping board 1 extending transversely of the machine below and parallel with that portion of the cable between sheave D and drum H. Slidably mounted within the board 1 are spaced pairs of bolts 2 and these bolts are secured within the end portions of a clamping block 3, there being nuts 4 engaging the bolts to hold them to the block. Heads 5 are provided at the lower ends of the bolts and coiled springs 6 are mounted on the bolts. These springs bear downwardly on the heads and upwardly against the board 1. The cable F extends between board 1 and block 3 and the springs 110

6 serve to bind the block 3 upon the cable so that it will be held securely between the block and board.

The drill G is adapted to be lowered to the surface in which the cut is to be made, cable F being fed between board 1 and block 3 during the lowering of the drill, it being understood that the spudding beam C is in its uppermost position during this operation. The bolts 2 are then tightened so as to increase the compression of the springs 6 and cause the cable to be gripped tightly. The machine is then set in motion and each time the spudding beam C moves downwardly the drill G will be raised while cable F will be held between the clamping members. Thus the cable will not work on the reel or drum H and the objectionable burning or wearing action of that portion of the cable on the drum will be eliminated.

What is claimed is:

1. The combination with a drum, a drill actuating cable, and means for shifting the cable independently of the drum to raise

and lower the drill engaging portion of the 25 cable, of relatively fixed and movable gripping members, and yielding means for binding said members upon the cable to hold the cable against excessive movement upon the drum.

2. In a drilling machine the combination with a main cable, a drum engaged thereby, and means for actuating the cable independently of the drum; of means interposed between the drum and said actuating means 35 for holding the cable against movement relative to the drum said means including relatively fixed and movable members having a cable receiving space therebetween and adjustable yielding means for binding the 40 members upon the cable in said space.

In testimony that I claim the foregoing as my own, I have hereto affixed my signature in the presence of two witnesses.

JONAH REYNARD.
